(57) **CLAIM**

I claim the ornamental design for a camera bracket, as shown and described.

DESCRIPTION

FIG. 1 is a front, right, and top perspective view of a camera bracket showing my new design.

FIG. 2 is a front elevational view thereof.

FIG. 3 is a rear elevational view thereof.

FIG. 4 is a left elevational view thereof.

FIG. 5 is a right elevational view thereof.

FIG. 6 is a top plan view thereof.

FIG. 7 is a bottom plan view thereof.

FIG. 8 is a front, right, and top perspective view thereof in an alternate configuration, in which the camera attachment piece is in the opposite orientation; and,

FIG. 9 is a front, right, and top perspective view thereof in an environment of use.

The broken lines in all figures depict portions of the camera bracket and environmental subject matter that form no part of the claimed design.
